UNITED STATES PATENT OFFICE.

WILLIAM P. FERGUSON, OF NEW YORK, N. Y.

DESIGN FOR A CAP FOR EXPLODING DYNAMITE-CARTRIDGES.

SPECIFICATION forming part of Design No. 28,949, dated June 28, 1898.

Application filed May 23, 1898. Serial No. 681,513. Term of patent 14 years.

To all whom it may concern:

Be it known that I, WILLIAM P. FERGUSON, a citizen of the United States, and a resident of New York, in the county of Kings and State of New York, have invented and produced a new and original Design for Caps for Exploding Dynamite-Cartridges, of which the following is a specification, reference being had to the accompanying drawings, forming a part thereof.

The essential feature of my design consists in a shell for exploding dynamite-cartridges having a cylindrically-shaped body portion tapering at one end to a point and diverging at the opposite end into a funnel shape.

In the accompanying drawings, Figure 1 is a view in side elevation. Fig. 2 is a longitudi-

dinal central section, and Fig. 3 is a cross-section.

A represents the body portion, of cylindrical form, *a* the pointed end, and *a'* the opposite funnel-shaped end.

What I claim is—

The design for a cap for exploding dynamite-cartridges, substantially as herein shown and described.

In testimony that I claim the foregoing as my invention I have signed my name, in presence of two witnesses, this 5th day of May, 1898.

WILLIAM P. FERGUSON.

Witnesses:

FREDK. HAYNES,
EDWARD VIESER.
